UNITED STATES PATENT OFFICE.

LOUIS SANDERS, OF BROOKLYN, NEW YORK.

DESIGN FOR A BELT.

SPECIFICATION forming part of Design No. 35,570, dated January 7, 1902.

Application filed December 13, 1901. Serial No. 85,860. Term of patent 3½ years.

To all whom it may concern:

Be it known that I, LOUIS SANDERS, a citizen of the United States, and a resident of the city of New York, borough of Brooklyn, in the county of Kings and State of New York, have invented and produced a new and original Design for a Belt, of which the following is specification, reference being had to the accompanying drawings, forming a part thereof, in

which—

Figure 1 is a plan view of a belt embodying the features of my design, and Fig. 2 is a transverse section on the line 2 2 of Fig. 1.

The leading features of the design consist of the upper and lower parallel bands or straps A and B and the plaited strip or strap C, which is carried between the other bands or straps independent thereof, a space intervening the contiguous edges of the central and outer members.

The minor features of the design consist in the transverse loops D, which occur at intervals in the length of the belt transversely thereof, and the apertured terminal E, extending from the outer face of the body of the belt.

Having thus described my invention, I claim as new and desire to secure by Letters Patent—

The design for a belt herein shown and described.

In testimony whereof I have signed my name to this specification in the presence of two subscribing witnesses.

LOUIS SANDERS.

Witnesses:

J. FRED. ACKER,
JNO. M. RITTER.
